(57) **CLAIM**

We claim the ornamental design for a cup holder, as shown and described.

DESCRIPTION

FIG. 1 is a front isometric view of a cup holder embodying the claimed design;
FIG. 2 is a front elevational view of the embodiment shown in FIG. 1;
FIG. 3 is a rear elevational view of the embodiment shown in FIG. 1;
FIG. 4 is a left side elevational view of the embodiment shown in FIG. 1;
FIG. 5 is a right side elevational view of the embodiment shown in FIG. 1;
FIG. 6 is a top plan view of the embodiment shown in FIG. 1; and,
FIG. 7 is a bottom plan view of the embodiment shown in FIG. 1.
